LIQUID HEATING DEVICE

Tage V. Pedersen, Roscoe, Ill.

Application September 16, 1948, Serial No. 49,489

10 Claims. (Cl. 123—142.5)

1

This invention relates to an improved heating device for use in obtaining a favorable temperature condition of the liquid contained in the jacket space of an engine, or the like.

I am fully aware of the many prior heating devices which have been proposed for obtaining and maintaining a reasonably favorable temperature condition of the cooling liquid in the jacket spaces of an engine, or the like. In principle, these prior devices have uniformly depended upon the establishment of a complete circulatory system from the heater chamber to the engine jacket and return. The major difficulty with these devices has been in the expensive installations required, that is in the requirement of specially prepared jacket tap ports, and the need for space to accommodate the necessary tubing leading between the heating device and each of the jacket ports. A further difficulty has been in the attempts to provide a high capacity heat source whereby the jacket liquid could be heated sufficiently to carry the heat into the normal radiator unit for the engine.

I have found that it is necessary only to gain a favorable temperature condition in the jacket spaces of an engine, and that a comparatively low capacity heater will maintain the jacket liquid sufficiently warm to reduce the viscosity of the lubricating oils on the cylinder walls and enable easy engine starting. Accordingly, an important object of this invention resides in the provision of a heating device which will accomplish the above stated purposes.

It is also an object of the invention to provide a simple heating device which is adapted for connection with the jacket space of an engine at only one jacket port, thereby simplifying the problem of installation and materially reducing the expense connected therewith.

A further object of my invention is to be found in the provision of a heater device which performs its function in an intermittent or percolator process of imparting heat to a relatively small volume of fluid and in which the fluid is rapidly converted to an expanded vapor capable of self-discharge into the larger volume of jacket fluid.

Other objects of the invention are to be found in the form, construction and assembly of the several cooperating parts of the present heating device, all of which contribute to the simple, unitary nature thereof, and conduce to its inexpensive initial cost.

The features and method of installing my improved heating device are clearly shown in the accompanying drawing, and a full understanding

thereof may be had from the description given with reference thereto.

In the drawing:

Fig. 1 illustrates one method of installing the present heating device in connection with a jacket structure of a liquid cooled engine, or the like;

Fig. 2 illustrates another installation of the heating device, as well as indicating its construction in longitudinal section, and

Fig. 3 is a transverse section of the device taken at line 3—3 in Fig. 2.

In the drawing, the presently improved heating device (Fig. 2) may be seen to comprise a tubular metal housing 1 having a reduced diameter throat zone 2 adjacent the externally threaded end nipple portion 3, a metal heater unit cell element 4 nested inwardly of the slightly diametrically enlarged open end portion 5 of the housing 1, and a closure cap 6 slidably mounted over the housing end 5. The cell element 4 is provided with a flange 7 at its outer open end, and this flange 7 is adapted to seat against the internal shouldered zone 8 of the housing 1. When assembled, the cell flange 7 is adapted to be brazed or otherwise affixed to the shouldered zone 8 to form a complete seal, whereby the interior space 9 of the housing is fully closed opposite the mounting nipple end 3.

The heating unit for disposition within the cell element 4 is comprised of a spool body 10 formed of ceramic or other insulator material, and an electrical resistance coil 11 carried by the spool. As indicated, the spool 10 is formed with an enlarged base end 12, a similarly enlarged head end 13 and an intervening cylindrical body zone 14 which is diametrically reduced. The base end 12 is formed with a diametral slot 15 which communicates with an axially directed bore 16, the latter bore extending through the spool and opening at the head end 13. The enlarged head end 13 of the spool is provided at one zone with a peripheral notch 17 which extends axially therethrough. The spool 10 is also provided with 40 axially directed and diametrically spaced sockets 18 into each of which a short terminal post element 19 is fixed.

The heating coil 11 is formed from a suitable electrical resistance wire, and is wound on the spool 10 in the following manner. One end of the coil wire is wound about one post element 19 and the wire is then threaded through the axial bore 16 and passed radially outwardly along the base end slot 15. The slot 15 is made sufficiently deep (axially of the spool) to open in the body

zone 14, and consequently the wire may be brought directly onto the body where it is wound in a spiral coil over the full length of the body 14. In order to prevent the coil turns from contacting, the body 14 is spirally grooved or superficially threaded to a depth sufficient for purposes of trapping each turn. After completing the coil 11, the end of the wire is dropped into the peripheral notch 17 and wound about the opposite terminal post 19.

The completed coil on the spool 10 is placed in the cell element 4, there first having been applied a coating of a nonconductive cement over the entire assembly to fix the same in place and assure that there can be no contact of the wire with the metal cell walls. The cap 6 is provided with an insulator bushing 20 in its center aperture, and a current supply cord 21 is passed through this bushing. The individual wire strands 22 of the cord 21 are separated, stripped of insulation and secured one to each of the terminal post elements 19 by means of solderless connectors 23. The opposite end of the cord 21 is provided with a proper plug (not shown) for connection into a 110 volt current source. The source may be either alternating or direct current.

Prior to pressing cap 6 into place on the enlargement 5 of housing 1, the outer end space thereof is filled with a body 24 of insulating cement or the like to secure and maintain the separate disposition of the current wires 22 and the post elements 19. It is now fully apparent that the heating unit is completely insulated against short circuiting contact with any adjacent portion of the metal of the cell 4, cap 6 or housing 1. It is also important to note, that the grooves or threaded channel formed in the surface of the spool body 14 serves to locate and retain the several turns of the coil 11 in spaced relation, some additional assistance being derived from the application of the nonconductive cement coating over the coil.

The heating device, as constructed and assembled in the manner above described, is adapted for mounting in a threaded port 24 formed in the boss zone 25 of a jacket wall 28 associated with the body or block 27 of an engine (not shown). The preferred location of the port 24 is at a low zone of the jacket space 28 for the engine. In Fig. 1, the nipple end 3 of the device is shown as threaded directly into the port 24, final turning up of the device being had by means of the tool engaging flats formed exteriorly on the surface of the throat zone 2. In this mounting, the heating device extends substantially horizontally of the engine and the fluid in the jacket space 28 flows into and fills the chamber or space 9 of the device. A preferred method of mounting the device is shown in Fig. 2, wherein the use of an adapter fitting 30 of angular type is shown. The fitting 30 is first threaded into jacket port 24 with its outer angularly directed end turned downwardly. The device may then be threaded into the fitting, whereby it will assume an angular position with its nipple end 3 uppermost. The engine cooling fluid will then flow downwardly into the space 9 of the device, and in this angular disposition of the device there will be no pocket or area likely to trap the fluid or fluid vapors generated by the heat passing through the walls of the cell element 4.

In operation, the heating device is threaded into the port 24 formed in the engine jacket wall at a low point of the entire jacketed space for such engine. The cooling fluid will then

flow by gravity into the chamber 9 of the device, and any air initially trapped in the chamber 9 will eventually be expelled. The cord 21 is then connected with a suitable source of current, and the heating coil 11 will then be energized. The coil 11 generates heat rapidly and in a concentrated or localized zone. The fluid in chamber 9 receives the heat and is rapidly changed to a vaporous condition, as steam, to cause its expulsion from the chamber 9 into the jacket space 28. After the heated vapors leave the chamber 9, the cooler liquid of the jacket will enter and, in turn, be converted to vapor by contact at the outer surfaces of the cell 4. This liquid-to-vapor generating and expelling process continues so long as the current is on the coil 11, and in this manner the entire body of jacket fluid may be warmed either by direct contact with the cell 4 or by mingling with the heated vapors passing from the device into the engine jacket. The action of the device is that of a percolator, in which a liquid is brought into a confined zone, and is heated rapidly to expand and vaporize the liquid, or a sufficient quantity thereof to effect its self-expulsion from the heating zone. In the present device, the inflow of liquid and the outflow of expanded liquid and vapor occurs through a common passage, thereby making the conditions of reverse flow intermittent. Consequently, there is no circulation, as such, through the device, and the expense and difficulty of providing a one-way circulating system is avoided.

Having now fully described and explained the preferred form of my invention, I wish it to be understood that certain structural modifications may be possible therefor, without avoiding the scope of the invention as defined in the following claims:

I claim:

1. The combination with an engine having a cooling liquid jacket space, of a heater device mountable in a wall of the jacket, the device being formed to provide a chamber for receiving jacket liquid and a restricted port opening to the jacket space, and a heating unit carried by said device in heat-exchange relation with the liquid in the chamber, such that jacket liquid flowing into the chamber through said port is thermally expanded and vaporized to cause its expulsion from the chamber and return through said port to the jacket space prior to a further flow of jacket liquid to the chamber.

2. In combination with a jacketed space for a cooling liquid, a housing mounted on the jacket and having a single restricted avenue of communication with the liquid in the jacket space, and means disposed in said housing for supplying heat to the liquid entering the housing whereby the liquid takes on heat and is vaporized sufficiently to cause its expulsion to the jacket space, by way of said single avenue of communication, said means comprising a cell element in direct contact with the liquid, and an electrical resistance coil in said cell element disposed in heat exchange relation closely adjacent the walls of the cell element.

3. In combination with an engine having a cooling liquid jacket space provided with a restricted port at a low zone of such jacket space, an electrically energized heating device mounted in said jacket port for heating the liquid, said device comprising a housing open at one end to the jacket space at said restricted port and through which liquid passes to the housing and vaporized liquid is expelled from the housing to

the jacket space, a cell element closing the opposite end of said housing and defining a housing chamber for the liquid, and an electrically energized heating unit disposed in said cell in heat-exchange relation with the walls thereof for rapidly vaporizing the liquid to cause its expulsion to the jacket space.

4. A heating device for use with an engine jacket cooling fluid, the jacket having a port in a wall thereof, said device including a tubular housing having a restricted passage nipple end for mounting connection at the jacket port and through which jacket fluid is constrained to pass to said housing and vaporized liquid is expelled from the housing to the jacket space, a tubular cell element closing the opposite end of said housing and having its walls spaced from the housing walls to define a chamber for jacket fluid, and an electrically energized heating unit mounted in said cell element in heat-exchange relation with the cell walls for rapidly vaporizing the liquid to cause its expulsion to the jacket space.

5. In combination with an engine having a cooling fluid jacketed space through which the fluid normally flows in cooling the engine, the jacket being provided with a port at a low zone thereof, a fluid heating device mounted at the jacket port for receiving fluid from the jacket, said device including a housing open at one end to said port by a restricted passage, an element closing the opposite end of said housing and extending thereinto in spaced and nested relation to form with the housing a chamber for jacket fluid, an electrically energized heating unit in said element in heat-exchange relation therewith to pass heat to the fluid in said chamber, the heated fluid being expelled from the chamber by vaporization for return to the jacket space by way of the port, and means electrically insulating and sealing the unit in said element.

6. The combination with an engine jacket space for cooling fluid and in which the jacket is provided with a port at a low point thereof, an elongate, tubular housing having a reduced diameter throat zone, a nipple end portion adjacent thereto, and an opposite open end, a cell element nested in said opposite end of the housing in spaced relation to form a chamber internally of the housing, the cell element having a flanged connection with the housing and adapted to seal the chamber at the flange, an electrically energized heating unit mounted in said cell in heat-exchange relation with the cell walls, means electrically insulating said unit from said cell and housing, a closure cap for said opposite end of the housing to retain the heating unit in position, and an adapter mounting said device in the jacket port with the longitudinal axis of said housing directed angularly to elevate the nipple end thereof above the chamber, whereby jacket fluid flows by gravity into the chamber and is expelled reversely through the nipple and adapter by vaporization effects upon heating.

7. A fluid heating device for connection with a body of fluid to be heated, the device including a housing open at one end zone for reversible fluid flow connection with the body of fluid, a cell element disposed in said housing and adapted to seal the opposite end zone thereof, the cell being

otherwise spaced from said housing to provide a chamber for receiving the fluid, a spool disposed in said cell and provided with opposite end flanges to space the intervening surface of the spool from the cell walls, a resistance wire wrapped about said spool surface, post elements on said spool for securing the ends of said wire in spaced relation, a current supply cord electrically connected at said post elements with said resistance wire, a body of insulating material embedding said post elements and connections in spaced relation, and a closure for said housing seated over and retaining the insulating body in position.

8. A heating device as defined by claim 7, and further characterized in that the intervening surface of said spool is surficially, spirally grooved to provide a seat for the resistance wire wrapped thereon, whereby to maintain the several turns of the wire in spaced relation and electrically separate.

9. A fluid heating device for connection with a body of fluid to be heated, the device comprising a cylindrical housing having one end reduced to provide a nipple for connection with the body of fluid, and the opposite end zone enlarged to provide an internal shouldered seat, a cylindrical cell element having a closed end and a flanged end, said element being disposed within said housing and connected thereto by said flange at the shouldered seat, the flange connection at said seat affording a seal closing the space between the cell and housing to provide a chamber for receiving fluid through said nipple, a spool element of insulating material in said cell and formed at its ends with flanges to retain the intervening portions spaced from said cell, an electrical resistance wire coiled about the intervening portion of said spool, means on said spool to anchor the respective wire end portions in spaced relation, means for supplying an electrical current to said resistance wire, and means closing the enlarged end of said housing and electrically insulating said wire anchor means from contact with the housing.

10. A fluid heating device as defined by claim 9, and further characterized in that the intervening portion of said spool element between its end flanges is surficially threaded to provide a retaining seat for said resistance wire.
